REMOTE CONTROL SYSTEM FOR
TYPEWRITERS

Henry L. Tholstrup, Rochester, N. Y., assignor to
International Business Machines Corporation,
New York, N. Y., a corporation of New York

Application September 25, 1948, Serial No. 51,178

6 Claims. (Cl. 197—19)

1

This invention relates to typewriting machines.

The primary object of the present invention is to provide a remote controlled typewriter system suitable for use in certain types of commercial establishments, such as restaurants, where it may be desired to transmit information concerning customers' orders and the like to a typewriter located at a point where the orders are made up, as in the kitchen of a restaurant.

Another object is to provide a remote controlled typewriter which may be operated under the control of any one of a plurality of separate stations, at each of which there is a keyboard for controlling all of the functions of the typewriter.

Another object is to provide a remote controlled typewriter system having provisions for preventing more than one station at a time from controlling the remote typewriter.

Another object is to provide an interlock and signal system by which all of the stations are interlocked and provided with signals so that the operating condition of the system may be shown at all times at any station and to prevent a second station from affecting the line circuits while another station is controlling the remote typewriter.

Other objects of the invention will be pointed out in the following description and claims and illustrated in the accompanying drawings, which disclose by way of example, the principle of the invention and the best mode, which has been contemplated, of applying that principle.

In the drawings:

Fig. 1 is a side elevation of the remote control typewriter.

Fig. 2 is a vertical section showing one of the keyboard units for controlling the typewriter.

Fig. 3 is a detail view showing the lock magnet for the remote control keyboard.

Fig. 4 is a wiring diagram.

In Figs. 1 and 3, the numeral 10 generally designates a commercial form of power operated typewriter, such as the well known "Electromatic," formerly known as the "International" and now known as the "IBM" electric typewriter. This machine has become well known in the art and, in view of this, only a very general description of it as modified to adapt it to remote control will be given herein. The typewriter 10 has all of its mechanism operated by power through the medium of a suitable power roller (not shown) controlled by key levers 11 (Fig. 1) which, when depressed, cause the type bars, the carriage re-

turn, tabulating, back space, and carriage spacing mechanisms to operate in a well known way.

For purposes of the present invention, the usual carriage 12 is modified to the extent of providing extensions 12a (Fig. 1) thereon for the purposes of rotatably supporting a suitable roll 13 of paper. The carriage is also provided with a single stop bar 14 similar to the ones disclosed in application Serial No. 593,367, filed May 12, 1945, by Henry L. Tholstrup, now Patent No. 2,439,497, dated April 13, 1948. The stop bar 14, through the medium of its stops 14a, controls a pair of marginal contacts MC which indicate when the carriage 12 is within a few spaces of the right-hand marginal position. As will be seen later herein, these contacts control a signal light which indicates to the operators at the remote control keyboards, the position of the carriage 12 of the typewriter. The contacts MC open when the carriage moves away from the right-hand marginal position, as when the carriage is returned.

The key levers 11 of the typewriter are operated by the key selecting solenoids KS (Fig. 1) which, when energized, pull down the key levers 11 to cause the various mechanisms of the typewriter to operate. The type bars have only upper case type, numerals, and special signs suited to the class of business in which the machine is used and the type basket is not shiftable. However, where it is necessary to print more characters, a two case machine may be used and a solenoid KS provided for the shift keys of the typewriter. With these modifications, the machine is rendered suitable for remote control by one or more separate keyboards, each capable of controlling the solenoids KS. These keyboards are designated stations A, B, and C in Fig. 4. One of the keyboards is shown in vertical section in Fig. 2 and consists of a base plate 20 provided with a plurality of posts 21 supporting a plate 22 parallel with the base plate 20. The plate 22 supports all of the mechanism of the remote keyboard. The remote controlling keys 23 correspond in number, position, and spacing to the keys of a standard typewriter keyboard, including the carriage return, tabular, and back space keys, and also including a space bar 24 which is constructed in the usual way and provided with a key lever similar to the key levers 23a for the keys 23.

The key levers 23a are pivotally mounted on a cross rod 25 (Fig. 2) carried by a cross bar 26 supported on the plate 22 by means of the frame

members 27 which may take the form of suitable brackets or posts. Also mounted on the plate 22 by means of the posts 28 is a key guide comb 29 which is slotted to accommodate the key levers 23a. At their forward or left-hand ends, the key levers are guided by a channel shaped key guide 30 supported by a cross bar 31 fixed to the top surface of the plate 22.

The plate 22 and the bar 31 are each provided with a row of holes which are vertically aligned and also aligned with the key levers 23a. Received in these holes are the short rods 33 of insulating material, the upper end of each rod coacting with a key lever 23a and the lower end coacting with a group of contacts which are operated each time the associated key lever 23a is depressed. On account of limited space, the contacts are arranged in two sets in a vertical row, each set being operated by a pair of adjacent keys. There are three contact members designated 34, 35, 36 for each key and the pins or rods 33 are of two different lengths so that each rests upon one of the contact members 34. In order to permit the longer rods 33 to reach down to the lower contact members 34, the upper contact members 34 are cut away at their ends to provide a clear space for the longer rods 33. Thus alternate key levers operate the members 34 in one vertical row.

The keys which ordinarily effect shifting of the type basket are intercoupled by a crank shaft 31 (Fig. 2) which is pivoted in the brackets 30a which form part of and support the key guide 30 so that the two keys always travel together when either one is depressed. These keys SK control a set of contacts SKC (Fig. 4) similar to the contacts 34, 35 and will be termed the start keys. The space bar 24 is provided with a somewhat similar construction including the crank shaft 31a so that, except for the fact that the keys 23 operate contacts, and do not control cam units by direct tripping, the keyboard is constructed similarly to the keyboard in the typewriter.

All of the keys, with the exception of the start keys SK, are provided with a common form of key lock which prevents more than one of the keys from being depressed at a time. In the present case the lock may consist of rollers 38 located underneath the key levers 23a between the key guide comb 30 and a strip 39 spaced from the key guide comb 30 by a separator strip 40 on which the rollers 38 rest loosely. The rollers are of just sufficient size to enable only one key to be depressed at a time and are normally kept close together in locking condition by a lock lever 41. (Fig. 3) pivoted at 42a on a bracket 42 carried by plate 22. A spring 43 urges this lever in counterclockwise direction. The forward end of this lever 41 is shaped like the key levers 23a and is guided by the key guide comb 30. Spring 43 holds the left-hand end (Fig. 3) of lever 41 depressed thereby locking all of the keys except the start keys SK against depression, the latter being cut away adjacent rollers 38 so as to be depressible when the remaining keys are locked.

A lock releasing solenoid LS connected to the rear or right-hand arm (Fig. 3) of lever 41 and mounted on plate 22 rocks the lever 41 clockwise to release the keys for operation.

The operation of the machine under the control of the remote keyboards will now be explained in detail with particular reference to Fig. 4 which comprises a wiring diagram of the system.

When the main switch S is closed, alternating

current will be supplied to the line wires W1, W2 which are common to all of the remote control stations and to the typewriter. This will start the typewriter motor M and also will energize the signal light L5 at the typewriter, indicating to the person in charge of the machine that the typewriter is in readiness for operation. It will be assumed that the carriage 12 of the typewriter is in its left-hand marginal position in readiness for writing a line on the strip from the roll 13 carried by the carriage 12 of the typewriting machine.

It will be assumed that the operator at station A wishes to transmit information to the typewriter and that none of the other remote controlled keyboards are in operation, that is, transmitting information to the typewriter. When the starting key SK is depressed at station A, the contacts SKC of this key will be closed. This allows a circuit to be established to energize relay R6 as follows: line wire W1 in station A, the contacts SKC for the key SK, the coil of relay R6, contacts R5B of relay R5, the contacts R4B of relay R4, to line wire W2. The starting key SK at station A must be held down as there is no provision on the remote control keyboards for maintaining these keys in depressed position. The contacts R6E will close and energize the signal lamps L3 for stations B and C over circuits from line wire W1, the lamps L3, contacts R5D, R4D of relays R4 and R5, and contacts R6E of relay R6, to line wire W2. The lights L3 are red lamps and at the stations B and C indicate to the operators at those stations that one of the other stations, in this case station A, is about to, or actually is, controlling the remote typewriter. As long as the contacts are held closed at station A, stations B and C cannot control the typewriter.

When the relay R6 is energized, the closure of its contacts R6B energizes relay R1 by a circuit from line wire W1, the coil of relay R1, and the contacts of relay R6B, to line wire W2. Relay R1 closes contacts R1B and causes the condenser C1 to charge to the potential of the power supply, but for the moment this has no effect. The lock release magnet LS and lamp L1 of station A are energized by a circuit from line wire W1, through contacts R6F of relay R6, the lock release magnet LS and the lamp L1 in parallel, through the rectifier R, to the line wire W2. This causes the keyboard lock for station A to become released and the light L1, which is a green light, indicates to the operator at station A that no other station is controlling the typewriter and that the line is clear for the transmission of data. None of the amber lights L2 will be energized because it has been assumed that the carriage of the typewriter is in the left-hand marginal position.

The operator now proceeds to operate the keyboard to transmit the desired character signals by depressing the keys and closing the contacts 34, 35, 36 selectively. Let it be assumed that the extreme left-hand key contacts 34, 35, 36, corresponding to the "A" character key at station A (Fig. 4), are closed. A circuit will be set up from line wire W1, through the contacts 34, 35, 36; the "A" solenoid KS, to line wire W2. The energization of this solenoid causes the typewriter to print the letter "A". In similar fashion, others of the solenoids KS will be rendered effective by the depression of the appropriate character keys at station A and cause the desired information to be written on the first line.

If the operator writes almost to the end of the line, the amber light L2 at station A will be light-

ed by the closure of the margin contacts MC which connects all of the amber lights L2 in parallel across the line wires W1, W2. The operator may wish to write more information than can be put on one line and, when the amber light lights, it is a warning to write only a few more characters and then to press the carriage return key. This will cause the carriage to return in the usual way since the carriage return key also is provided with a pair of contacts 34, 35, 36 and 10 the typewriter has a solenoid CRS for rendering the carriage return mechanism of the typewriter effective. As soon as the carriage is returned, the contacts MC open and extinguish the amber lights and the operator may now proceed to 15 type another line.

When the transmission of the desired data is finished, the operator will release the key SK permitting the contacts SKC to open and de-energizing the relay R6. Due to the opening of the contacts R6B, the relay R1 will be deenergized allowing the contacts R1A to close. This connects the charged condenser C1 in parallel with the relay R2 and causes the relay R2 to be energized momentarily thereby closing the contacts R2A of the relay R2. Contacts R2A connect the carriage return solenoid CRS across the line wires W1, W2, and effect an automatic return of the carriage. This insures that whenever the operator of any station finishes the use of the remote control keyboard to transmit data, the carriage will always be positioned in readiness for transmission of data by another station without the necessity for first returning the carriage before beginning transmission, since the carriage might be left in an intermediate position and there is no means of indicating this fact.

Whenever any of the relays R4, R5, R6 which correspond to stations C, B and A, respectively, are energized to begin the transmission of data, the relay R1 will be energized as described and, aside from the advantage discussed above, the contacts R1C will close and energize the signal light L4, which may be a red light, denoting to the operator at the typewriter that a message is being transmitted.

It will be noted by reference to the wiring diagram that for each relay coil R4, R5, R6 there is a set of contacts like R5A in series therewith for the other two relays so that energization of any of these relays prevents the energization of the other two. For example, the coil of relay R4 is in series with the contacts R5A, R6A, so that energization of either of these relays prevents the energization of relay R4. Relay R5 is in series with the contacts R6C, R4A so that relay R5 cannot be energized when either relay R4 or R6 is energized. The contacts R4F, R5F, R6F, cause the lock release magnet LS for the corresponding station to be energized to release the keyboard for that station whenever the key SK for that station is operated, as was explained above in reference to station A and relay R6.

There is a possibility that power failure, for example, may cause the carriage to be stopped in an intermediate position. In order to enable the carriage to be returned to the margin under these conditions, the carriage return key lever of the typewriter is provided with a finger piece to enable this key to be depressed by hand by the person in charge of the typewriter and the remaining key levers of the typewriter are masked by a plate which has an opening to permit the

carriage return key lever, but no other key lever, to be operated.

One application for a system of the nature described above is in the restaurant business for the transmission of food orders to the cooks. This is usually done by means of a system of microphones and loud speakers but has been found to be somewhat imperfect due to the difficulty of fixing the blame for errors in filling orders sent back to the kitchen by the customer resulting in considerable loss from food thrown away. Also, due to noise, errors are committed due to the cooks misunderstanding instructions and filling orders incorrectly.

The stations may be located at the different order counters or positions and used to transmit the orders to the cooks in the kitchen. The typewriter may have special types to reduce the time and effort in transmitting the order. For example, the following special types might be used to transmit sandwich orders: "WH", white bread; "RY", rye bread; "WW", whole wheat bread; "MY", mayonnaise; "MU", mustard; "RU", Russian dressing; etc.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination, a power operated typewriting machine having a series of electromagnets for controlling the functions of the typewriting machine, a carriage, and contact means actuated when the carriage is at the line-end position; a system of remote keyboards for controlling said machine, each keyboard including keys and contact means actuated thereby for selectively closing circuits to said electromagnets, means to normally lock the keyboard against operation, a magnet for releasing the locking means, a release key for controlling said lock release magnet, and a series of signal lights designating line end, line clear, and line not clear, said line end signal light being controlled by said line end contact means; and control relays, one for each of said keyboards, each control relay being controlled by the release key for the corresponding keyboard and controlling circuits to said last two signal lights and to said lock release magnet to energize the lock release magnet and energize the line clear light of a keyboard for which the release key is operated and to energize the line not clear lights for the other keyboards and prevent energization of the relays for the other keyboards.

2. In combination, a power operated typewriting machine having a series of electromagnets for controlling the functions of the typewriting machine including carriage return; a system of remote keyboards for controlling said machine, each keyboard including keys and contact means actuated thereby for selectively closing circuits to said electromagnets, means to normally lock the keyboard against operation, a magnet for releasing the locking means, a release key for controlling said lock release magnet, and a series of signal lights designating line clear, and line not clear; control relays, one for each of said

keyboards, each control relay being controlled by the release key for the corresponding keyboard and controlling circuits to said signal lights and to said lock release magnet to energize the lock release magnet and energize the line clear lamp of a keyboard for which the release key is operated and to energize the line not clear lights for the other keyboards and prevent energization of the relays for the other keyboards, and means effective upon release of the release key to close a circuit to the carriage return electromagnet.

3. In combination, a power operated typewriting machine having a series of electromagnets for controlling the functions of the typewriting machine; a carriage, and contact means actuated when the carriage is at the line-end position; a system of remote keyboards for controlling said machine, each keyboard including keys and contact means actuated thereby for selectively closing circuits to said electromagnets, means to normally lock the keyboard against operation, a magnet for releasing the locking means, a release key for controlling said lock release magnet, and a series of signal lights designating line end, line clear, and line not clear, said line end signal light being controlled by said line end contact means; control relays, one for each of said keyboards, each control relay being controlled by the release key for the corresponding keyboard and controlling circuits to said last two signal lights and to said lock release magnet to energize the lock release magnet and energize the line clear light of a keyboard for which the release key is operated and to energize the line not clear lights for the other keyboards and prevent energization of the relays for the other keyboards; and a signal light at said typewriting machine energized by one of said relays when the release key of any keyboard is operated to call attention to the fact that the typewriting machine is about to be operated under control of a remote keyboard.

4. In combination, a power operated printing machine having a series of electromagnets for selectively controlling the functions of the printing machine; a system of remote keyboards for controlling said machine, said keyboards including keys and contact means actuated thereby for selectively closing circuits to said electromagnets, means to lock the keyboards against operation, magnets for releasing the lock means, release keys for controlling said lock release magnets, and signal lights designating line clear, and line not clear; and control relays for said keyboards,

said control relays being controlled by the release keys and controlling circuits to said signal lights and to said lock release magnets to selectively energize the lock release magnet and energize the line clear light of a keyboard for which the release key is operated and to energize the line not clear lights and prevent energization of the relays for the remaining keyboards.

5. In combination, a power operated typewriting machine having a series of electromagnets for controlling the functions of the typewriting machine; a system of remote keyboards for controlling said machine, said keyboards including keys and contact means actuated thereby for selectively closing circuits to said electromagnets, means to normally lock the keyboards against operation, magnets for releasing the lock means, and release keys for controlling said lock release magnets; and control relays, one for each of said keyboards, each control relay being controlled by the release key for the corresponding keyboard and controlling circuits to said lock release magnets to energize the lock release magnet of a keyboard for which the release key is operated and to prevent energization of the lock release magnets for the remaining keyboards.

6. In combination, a power operated typewriting machine having a series of electromagnets for controlling the functions of the typewriting machine; a system of remote keyboards for controlling said machine, said keyboards including keys and contact means actuated thereby for selectively closing circuits to said electromagnets, means to normally lock the keyboards against operation, magnets for determining when the lock means is to be effective and ineffective, respectively, and release keys for controlling said magnets; and control relays, one for each of said keyboards, each control relay being controlled by the release key for the corresponding keyboard and controlling circuits to said magnets to render ineffective the locking means for the keyboard associated with an operated release key and prevent release of the locking means for the remaining keyboards.
